Attorney

UNITED STATES PATENT OFFICE.

GEORGE W. SMIDLEY, OF NEW HOLLAND, OHIO.

HINGE AND SUPPORT FOR CLOSURES.

Application filed August 26, 1924. Serial No. 734,284.

To all whom it may concern:

Be it known that I, GEORGE W. SMIDLEY, a citizen of the United States, residing at New Holland, in the county of Pickaway, 5 State of Ohio, have invented certain new and useful Improvements in Hinges and Supports for Closures; and I do hereby declare the following to be a full, clear, and exact description of the invention, such as 10 will enable others skilled in the art to which it appertains to make and use the same.

This invention relates to new and useful improvements in closures, and particularly to hinged closures.

15 One object of the invention is to provide a closure which is adapted for use in connection with a hog feeder, pen, or the like, and which is provided with novel means for attaching the same to the feeder, pen 20 or the like, whereby the closure may be easily swung into open position, or closed position.

Another object is to provide a device for 25 hingedly connecting the closure to the feeder, or pen, and which will serve as a support for the closure when in open or closed position.

Other objects and advantages will be apparent from the following description when 30 taken in connection with the accompanying drawing.

In the drawing:

Figure 1 is an end view of an enclosure 35 for hogs, showing the closure in closed position.

Figure 2 is a similar view showing the closure in open position.

Figure 3 is a vertical transverse sectional view through the enclosure and closure, in 40 the position of Figure 1.

Referring particularly to the accompanying drawing, there is shown an enclosing pen for confining hogs, the opposite longer side walls 10, of which, are inclined upwardly and inwardly, as clearly seen in Figure 3, one of the vertical end walls 11 being provided with an access door 12. On the top of the pen there is disposed the closure 13, which has the vertical end walls 14, and 45 the upwardly converging top wall portions 15. In each of the vertical end walls 14 there are formed the ventilating openings 16. Depending aprons 17 are disposed between the outer ends of the end walls, and 50

connected thereto, and to the longer edges 55 of the wall portions 15, said aprons being disposed at an angle to lie parallel with the inclined walls of the pen.

Secured to the inner face of each end wall 14, of the closure 13, is the upper end 60 of a flat metal bar 18, said bar extending downwardly at right angles to the lower edge of the closure, and being pivotally connected to the outer face of the end wall 11 of the pen. A similar, but slightly longer 65 metal bar 19 is mounted on the pivot which carries the bar 18, and is disposed outwardly of the end wall 11, while the upper end of the bar 19 is secured to the inner face of the end wall 14, in such position that it 70 extends at an acute angle to the bar 18.

When the closure is in closed position one side thereof is supported by the shorter bar 18, which stands vertically, as clearly seen in Figure 1, while the other side of the closure carries the blocks 20, in the inner angles of the corners thereof, for contact with the upper edges of the side and end walls of the pen, to support said other side of the closure. 75

When the closure is in open position, as seen in Figure 2, one of the longer edge portions rests against the adjacent inclined side wall 11, of the pen.

By reason of the fact that the longer sides of the pen are inclined upwardly and inwardly, there will be no danger of the closure being blown out of place, by the wind, when the closure is in open position, and resting against said side.

Particular attention is called to the fact that the upper ends of the metal bars 18 and 19 are secured to the closure, and the lower ends pivoted to the end walls of the pen, at one side of the center of the pen. This arrangement causes the greater part of 90 the weight of the closure to lie at one side of the pen, with the result that the closure will remain in closed position against any winds of reasonable strength. Also, when the closure is in open position, and resting 95 against one of the inclined sides of the pen, it will be difficult for wind to blow the closure into closed position.

What is claimed is:

The combination with an enclosure and a 105 cover therefor, of a hinge means comprising vertically disposed bars secured to the ends of the cover, inwardly thereof, and adja-

cent one long side thereof and having their other ends pivotally connected to the ends of the enclosure, externally thereof and inwardly of a long side thereof, and obliquely extending bars pivotally connected to the said ends of the enclosure coincidently with the adjacent ends of the first bars and having their other ends secured to the inner

faces of the said ends of the cover adjacent the intermediate portions thereof, whereby to permit said cover to be swung into a position with its enclosure closing portion against the said longer side of the enclosure. ¹⁰

In testimony whereof, I affix my signature.

GEORGE W. SMIDLEY.
